CLAIM

The ornamental design for a vehicle-mounted display, as shown and described.

DESCRIPTION

FIG. 1 is a front elevation view of a vehicle-mounted display comprising the new design, the rear elevation view comprising a mirror image thereof;

FIG. 2 is a left side elevation view thereof, the right side elevation view comprising a mirror image thereof;

FIG. 3 is a top plan view thereof; and,

FIG. 4 is a perspective view thereof, the vehicle shown in broken line is included for the purpose of illustrating environment.

The features shown by broken line in FIGS. 1 through 4 form no part of the claimed design.
